F. J. KALTEYER

UNIVERSAL BLADE HOLDER FOR SHARPENING DEVICES

Filed June 24, 1920

INVENTOR.

Frederick J. Kalteyer,

BY

John J. Anderson, ATTORNEY.

UNITED STATES PATENT OFFICE.

FREDERICK J. KALTEYER, OF PHILADELPHIA, PENNSYLVANIA, ASSIGNOR TO ELECTOSTROP MANUFACTURING COMPANY, A CORPORATION OF PENNSYLVANIA.

UNIVERSAL BLADE HOLDER FOR SHARPENING DEVICES.

Application filed June 24, 1920. Serial No. 391,481.

To all whom it may concern:

Be it known that I, FREDERICK J. KALTEYER, a citizen of the United States, residing in Philadelphia, in the county of Philadelphia and State of Pennsylvania, have invented certain new and useful Improvements in Universal Blade Holders for Sharpening Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to blade holders for razor blades employed in razor sharpening devices. It has for its object to provide a holder for safety and for old style razors, and by reason of its adaptability for holding different styles of safety blades as well as the old style razors may be appropriately designated as a universal blade holder. The holder has various features of construction whereby it is adapted for securely holding the different types of razor blades; and also features whereby an old style razor-blade may be readily adjusted and held in proper position for effective honing or stropping. It also possesses features of construction whereby simplicity, strength and efficiency are obtained.

To the accomplishment of the foregoing and such other objects as may hereinafter appear the invention consists in the features hereinafter particularly described and then sought to be clearly defined by the claims, reference being had to the accompanying drawing forming a part hereof, and in which—

Figure 1 is a front elevation of parts of a blade sharpening device, showing the blade-holder in position;

Figure 2 is a perspective view of the blade-holder;

Figure 3 is a bottom-plan view of the holder;

Figure 4 is a front view of the holder showing a safety-blade positioned therein, and with a portion of the spring arms broken away;

Figure 5 is a horizontal section, on an enlarged scale, through the lower portion of

one of the jaws, the end views being cross sections of the main view on the lines *a—a* and *b—b*, respectively.

In the drawing the numeral 1 designates in a general way a part of any suitable sharpening device having an overhanging arm 2 from which the blade holder is suitably supported so that the blade will be positioned between honing or stropping rolls 3.

The blade-holder is formed from a blank which is cut or stamped and shaped so as to form two spring prongs or arms 3' adapted to be clamped to the overhanging arm of the machine so that the two arms will hold or press the blade with spring pressure against the honing or stropping roll that will be brought against the blade. From the lower connecting neck of these prongs or arms depends a jaw 4, while the portion of the metal from between the prongs is bent outwardly and then inwardly to form a loop member 5 and then bent downwardly to form a second jaw 6. One of the jaws, for instance jaw 4, is slotted at opposite ends and the slotted portions bent inwardly to form centering prongs or lips 7 designed to enter openings usually formed in some types of safety blades so as to serve in positioning the blade properly between the clamping jaws as illustrated in Figure 4. One jaw is also formed with inwardly bent lips 8 which serves as a bearing for the upper edge of a safety blade having only one cutting edge, and they also serve to prevent side movement of one jaw beyond the edges of the other jaw beyond which they may project as illustrated in Figures 1 and 2. Both jaws are formed at their lower edges with transversely extending grooves 9 and to one side of each groove are outwardly extending bosses or studs 10, the jaw 4 being formed with two of the studs and the jaw 6 with one positioned substantially centrally or midway between the two studs of the other jaw, and each stud is formed with a transverse groove 11. The grooves 9 and 11 are designed to form seats for the opposite sides of the back of an old style razor blade and prevent it from slipping when gripped by the jaws; and the end grooves in jaw 4 also serve to facilitate or direct the proper seating of such razor-blade between the

100
105

jaws. The bosses or studs on the gripping faces of the jaws constitute or afford three points of contact with the blade gripped by the jaws which insures a better grip 5 on the blade, and if the blade, as an old style razor, has a rounding or curved back the tendency of the blade to slip or change its position is guarded against. The jaws are drawn together to clamp the blade in 10 place by a threaded bolt 12 and thumb nut 13 between which nut and one of the jaws is a thimble or sleeve 14. The beaded end of the bolt is formed with an angular shoulder 15 which fits in an elongated slot 16 in the jaw and prevents the bolt from turning when the thumb nut is screwed up; and this elongated slot permits a limited 15 vertical adjustment of that jaw when desirable. This is sometimes necessary as old 20 style razors do not always have the back project to the same extent beyond both sides of the razor blade. When such is the case the blade would stand obliquely to one side or the other of a vertical line, according as the excess projection may be to 25 one side or the other, and under such circumstances the blade would not stand in proper position for honing or stropping. To bring the blade into proper position an 30 adjusting screw 17 is passed through the lower member of loop 5 and threaded into the upper member so that by expanding or contracting the loop as necessary the jaw will be lowered or raised to the extent necessary to tilt and bring the blade from an oblique position to a proper vertical position 35 for honing or stropping. In Figure 1 the dotted lines indicate the position of the jaw and loop when the blade is in one oblique position and the full lines indicate the expansion of the loop to tilt the blade into the vertical position indicated by full lines. If the blade when placed between the jaws should stand obliquely in the other direction 40 from that indicated in Figure 1, then the loop would be contracted to bring the blade into vertical position for honing or stropping.

I have illustrated and described the preferred details of construction in the form 50 of blade-holder illustrated but changes can

be made in the details and essential features of the invention retained.

Having described my invention and set forth its merits what I claim is:

1. A blade-holder for sharpening devices, said holder comprising oppositely disposed gripping jaws formed at their lower edges with inwardly projecting studs to form gripping contact points against opposite sides 60 of a blade, a stud on one jaw being disposed to project intermediate of studs on the opposite jaw.

2. A blade-holder for sharpening devices, said holder comprising oppositely disposed gripping jaws formed at their lower edges with a plurality of gripping contact points for a blade and disposed to have the contact point of one jaw to lie to one side of 65 a contact point of the opposite jaw.

3. A blade-holder for sharpening devices, said holder comprising oppositely disposed gripping jaws each formed with transversely extending grooves at the free ends of the jaws, and inwardly projecting studs 75 formed with transversely extending grooves.

4. A blade holder for sharpening devices, said holder comprising oppositely disposed gripping jaws with a loop formed at the upper portion of one jaw, and means for 80 contracting and permitting expansion of said loop for vertical adjustment of its attached jaw.

5. A blade holder for sharpening devices, said holder comprising oppositely disposed 85 gripping jaws, one jaw being an extension of spaced parallel spring supporting arms and the other being a continuation of a portion removed from between said arms shaped into a loop and extended to form 90 the second jaw, means for contracting and permitting expansion of said loop to effect vertical adjustment of the attached jaw, and means for contracting one jaw towards the other.

In testimony whereof I affix my signature in presence of two witnesses.

FREDERICK J. KALTEYER.
